(57) **CLAIM**

The ornamental design for a clip for refractory anchor, as shown and described.

DESCRIPTION

FIG. 1 is a perspective view of a clip for refractory anchor constructed in accordance with the present invention;

FIG. 2 is a bottom view of a clip for refractory anchor as shown in FIG. 1;

FIG. 3 is a rear view of a clip for refractory anchor as shown in FIG. 1;

FIG. 4 is a top view of a clip for refractory anchor as shown in FIG. 1;

FIG. 5 is a front view of a clip for refractory anchor as shown in FIG. 1;

FIG. 6 is a right side view of a clip for refractory anchor as shown in FIG. 1;

FIG. 7 is a sectional view taken along section line 7—7 of FIG. 4; and,

FIG. 8 is a perspective view of a clip for refractory anchor as shown in FIG. 1 shown in use.

The broken line showing of a refractory brick in FIG. 8 is included for the purpose of illustrating environment and forms no part of the claimed design.
